US00D967847S

(12) **United States Design Patent** (10) **Patent No.:** **US D967,847 S**
(45) **Date of Patent:** **** Oct. 25, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, Portland, OR (US)

(73) Assignee: **Apple Inc.**, Cupertino, CA (US)

(**) Term: **15 Years**

(21) Appl. No.: **29/822,142**

(22) Filed: **Jan. 6, 2022**

Related U.S. Application Data

(63) Continuation of application No. 29/800,625, filed on Jul. 22, 2021, now Pat. No. Des. 941,872, which is a continuation of application No. 29/740,329, filed on Jul. 2, 2020, now Pat. No. Des. 926,215, which is a continuation of application No. 29/706,105, filed on Sep. 18, 2019, now Pat. No. Des. 889,503, which is a continuation of application No. 29/683,939, filed on Mar. 18, 2019, now Pat. No. Des. 862,508, which is a continuation of application No. 29/642,082, filed on Mar. 27, 2018, now Pat. No. Des. 849,780, which is a continuation of application No. 29/582,325, filed on Oct. 27, 2016, now Pat. No. Des. 815,140.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines depict a display screen or portion thereof, and form no part of the claimed design.
